UNITED STATES PATENT OFFICE.

JOSEPH J. CARR, OF WILKES-BARRÉ, PENNSYLVANIA, ASSIGNOR OF ONE-HALF TO DOMINIC F. SWEENEY, OF SAME PLACE.

SAND-SIFTING MACHINE.

SPECIFICATION forming part of Letters Patent No. 378,129, dated February 21, 1888.

Application filed March 31, 1887. Serial No. 233,138. (No model.)

To all whom it may concern:

Be it known that I, JOSEPH J. CARR, of Wilkes-Barré, in the county of Luzerne and State of Pennsylvania, have invented certain new and useful Improvements in Sand-Sifting Machines; and I do hereby declare the following to be a full, clear, and exact description of the invention, such as will enable others skilled in the art to which it appertains to make and use the same.

My invention relates to an improvement in sand-sifting machines.

On the 12th day of February, 1887, I filed an application for patent on an improved sand-sifting apparatus, in which device rotary agitators were made to have a spring-bearing upon the surface of a stationary cylindrical screen of wire-cloth.

The object of my present invention is to improve the construction of this sand-sifting device by the provision of practical features which are not therein shown.

With this object in view my invention consists in certain features of construction and combinations of parts, that will be hereinafter described, and pointed out in the claims.

Referring to the drawings making a part of this specification, Figure 1 is an end elevation of the improved sand-sifting machine. Fig. 2 is a view of the opposite end of the sifting-machine. Fig. 3 is an end elevation of the machine mounted upon a frame and wheels to permit its transportation from one point to another. Fig. 4 is a side elevation in section of the sand-sifter. Fig. 5 is a view of the screen removed from the machine. Fig. 6 is a view of a screen-supporting roller removed from the sifting apparatus. Fig. 7 is a side or edge view of the screen material, showing the manner of connecting two sections.

In Figs. 1 and 2, B represents the end portions of the frame of the machine, which have each a central hub perforated for the reception of shaft-journals *a*. The edges of the frame-pieces are each made integral with cylindrical flanges C, and also have depending flanges B', cast to project from the lower portions of the laterally-projecting flanges C. (See Fig. 4.) The upright brackets *c c* are formed upon the upper surface of the cylindrical flanges C.

The end plates, B, are held in rigid connection by the bolts 1 2 3 4, which have securing-nuts adjusted to bear upon each side of the plates B' and the lower part of the upright brackets *c c*, in which holes are made for the insertion 55 of these bolts.

The shaft I is supported at its ends *a* to revolve in the end plates, B. The circular flanges A A' are mounted upon this shaft and secured in place by jam-nuts *g g*, which are placed on the threaded body of the shaft I at proper points to engage the sides of the plates, as shown in Fig. 4, and it will be seen that the flanges A A' are preferably located to rest in the same vertical plane with the inner edges 65 of the cylindrical flanges C, which will afford sufficient space to intervene between these flanges and the end plates, B.

The flanges A A' are perforated at spaced intervals, *b*, (see Figs. 1 and 2,) to receive the sand-agitators J, which are bent at their ends to form cranks of equal throw, the journaled ends of which enter the perforations *b* and are permitted to vibrate in these bearings.

Upon the upper ends of the bracket-arms *c* 75 the rollers L L are loosely mounted to rotate in holes made for their reception in these arms. These rollers are provided to receive and sustain the screen-wire sections G G, which are rigidly attached by their free ends to the rollers by clamping-bolts, as shown in Fig. 6, the nuts of the clamping-bolts *s* being embedded in recesses in the rollers to prevent injurious abrasion of the wire screen when it is wrapped around the rollers.

The screen G is preferably made in several sections, as shown in Fig. 5, which are connected by hooking their folded edges into the bent edges of plates D, which are similarly folded to produce hooks on their parallel sides, 90 the connection thus effected being secured from displacement by the insertion of the bolts D', the T-heads of which have a bearing upon the outer surface of the screen-wire cloth at the joined hooked edges of the several sections to 95 render them continuous.

When the screen G G is mounted on the rollers L L, the slack material is wrapped upon the bodies of said rollers, the edges of the screen having a contact with the cylindrical flanges 100

C, the contact just mentioned holding the screen in cylindrical form, with the interior surface of the same clear of all obstructions. The screening-cloth is made to bear upon the longitudinal bolts 3 4, that are inserted in the upright brackets *c c*. Upon the rotation of the rollers L the screen is drawn tightly and held so by the locking action of the pawls *p* with the ratchet-wheels H, which are rigidly secured upon the outer ends of the rollers L in proper position to permit such an engagement of the pawls, as shown in Fig. 1.

The agitator-bars J are provided with regulating-levers *e*, which are attached to the outer ends of the crank ends *b*, that project through the flanges A A', the levers *e* having springs *e'* fastened to their free ends and adapted to hold said levers in contact with eccentrics F, which are made to bear upon the levers and regulate the relative position of the scraper portions *m* of the agitator-bars J with regard to the interior surface of the screen G. It is apparent that by the adjustment of the cams F these bars J may be made to have a clearance space provided between their scraper-edges *m* and the opposed surface of the screen or be caused to lie upon this screen, as is desired.

The yielding action of the springs *e'* will afford a proper relief to the bars when a rigid impediment—such as iron scrap—is lodged in the screen, and thus injury to the wire-netting of the screen is avoided.

A scrap-box, O, is fixed to one end of the frame B, preferably at the center, to receive the scrap-iron or other refuse matter that accumulates in the screen. This material can be removed by loosening one of the rollers L, to produce a slackening of the screen material opposite the scrap-box, and if the machine is tipped or inclined to cause the débris in the screen to slide toward the box O it will enter it and free the screen of the same. The roller can then be revolved to tighten the screen and work be resumed, the operation of removal of the scrap or other refuse occupying but a few minutes.

The rollers L and center shaft, I, are provided with cranks to operate them. The shaft 50 I may have fast and loose pulleys secured in place to drive it and its attached screening mechanism if a stationary sifting-machine is to be employed.

This sand-sifting machine may be made portable by the provision of a frame, E, that is preferably affixed to the lower portions of the end plates, B, of the machine, to afford a means of securing an axle, E', thereto, the wheels E'', which are mounted on the axle to 60 revolvethereon, forming a transporting device which will permit the removal of the machine to any desired point for use.

It is evident that screens of different sizes of

meshed fabric may be employed, and if these are made continuous the screen can be changed 65 to suit different grades of material by simply revolving the rollers to give proper position to the screen, which may be tightened in the manner already described.

The construction of the screen in several sections will permit a damaged section to be readily removed, and repairs be thus made to the screen in an expeditious manner.

Slight changes might be made in the constructive features of this device without departure from the spirit and scope of the invention. I do not therefore desire to restrict myself to the exact forms shown; but,

Having fully described my invention, what I claim as new, and desire to secure by Letters Patent, is—

1. In a sand-sifting machine, the combination, with two end plates, two rollers mounted on the end plates, a screen secured to these rollers, and an adjustable means of holding the 85 rollers from rotation, of a center shaft mounted to rotate, two circular flanges secured to the shaft, and sand-agitator bars pivoted in these flanges, substantially as set forth.

2. In a sand sifting machine, the combination, with two end plates having projecting flanges and longitudinal connecting-bolts and jam-nuts, a center shaft, circular flanges, and sand-agitators adjustable with regard to the screen, of a screen, two supporting-rollers attached to the screen, and a means of securing the rollers from rotation, substantially as set forth.

3. In a screen for a sand-sifting machine, the combination, with the sections of screen-netting or wire-cloth formed with bent or hooked edges, of connecting-plates having corresponding hooked edges to engage the edges of the wire-cloth and clamping-bolts that pass through these attached hooked portions to bind them together, substantially as set forth.

4. In a sand-sifting machine, the combination, with two end plates, longitudinal securing-bolts, a screen, and two rollers adapted to hold the screen in stretched condition, of a center shaft, two circular flanges, sand-agitators having cranks on their ends pivoted to swing in holes in said flanges, levers fixed to the pivot ends of these cranks, cams that are adapted to move the scraper-edges of the agitators toward and from the screen, and springs attached to the levers to permit a yielding action of the sand-agitators, substantially as set forth.

In testimony whereof I have signed this 120 specification in the presence of two subscribing witnesses.

JOSEPH J. CARR.
